(57) **CLAIM**

The ornamental design for a vehicle side panel configuration, as shown and described.

DESCRIPTION

FIG. 1 is a front perspective view of a vehicle side panel configuration showing my new design;

FIG. 2 is a rear perspective view thereof;

FIG. 3 is a side elevational view thereof;

FIG. 4 is a front perspective view of a vehicle side panel configuration showing a second embodiment of my new design;

FIG. 5 is a rear perspective view of FIG. 4; and,

FIG. 6 is a side elevational view of FIG. 4.

The portions of the vehicle shown in broken lines are for illustrative purposes only and form no part of the claimed design.
